UNITED STATES PATENT OFFICE.

GEORGE J. A. MOLIQUE, OF ROXANA, ILLINOIS.

CLOTHESLINE HOLDER.

Application filed February 3, 1927. Serial No. 165,636.

This invention relates to holders for clothes lines.

An object of the invention is the provision of a device which is adapted to automatically clamp the free end or a portion of a clothes line to a fixed support and in which it is only necessary to insert the line in the device whereby the weight on the line will increase the clamping action for aiding in maintaining the end of the line against movement.

A further object of the invention is the provision of a simple, efficient and durable device adapted to clamp the end of the clothes line to a fixed support and in which a slidably mounted jaw is adapted to be automatically actuated by the weight on the line for aiding in maintaining the jaw in rigid clamping relation with the line.

This invention will be best understood from a consideration of the following detailed description in view of the accompanying drawings forming a part of the specification; nevertheless, it is to be understood that the invention is not confined to the disclosure, being susceptible of such changes and modifications which shall define no material departure from the salient features of the invention as expressed in the appended claim.

Figure 1 is a longitudinal view in elevation of a clothes line secured in position by my improved device.

Figure 2 is a side view in elevation of the clamp,

Figure 3 is a view in perspective of the opposite or outer side of the clamp, and

Figure 4 is a vertical section taken along the line 4—4 of Figure 2.

Referring more particularly to the drawings, 10 designates a post having an eye 11 secured therein and to which one end of a rope 12 is secured. The other end 13 of the rope is adapted to be secured to a fixed support 14 by means of a clamp generally designated by the numeral 15.

The clamp includes a housing formed of one piece of sheet metal and comprises a side wall 16 having a horizontal top 17 with the side wall being inclined to the horizontal along the lower edge as shown at 18. The side wall is provided with a slot 19 which is substantially parallel to the inclined edge 18, but is inclined at an acute angle to the horizontal top 17. Rising from the inner end of the top member 17 is a securing flange 20,

while a securing flange 21 extends laterally from the inner edge of the side wall 16. These two flanges are adapted to be secured to the fixed support 14.

Slidably mounted in the housing is a clamping bar 21 of substantially wedge formation and is provided with a plurality of teeth 22 along its upper edge. The clamping bar is maintained in position within the housing and with the teeth 22 in spaced relation with the top 17 by means of a pair of screws 23 and 24. The screws being threaded through passages 25 in the sliding clamp 21. The screws are provided with heads 26 forming a shoulder in engagement with the outer face of the wall 16 so that the inner face of the clamp 21 is maintained in close sliding contact with the inner face of the side wall 16.

It will be noted that the teeth 22 are curved as shown at 27, to receive the free end 13 of the rope, the rope being carried around the end of the clamp block and seated within a groove 28 on the inner lower edge of the clamping block 21.

The rope 12 is secured at one end to the eye 11 of the post 10 and the other end of the rope is inserted within the clamping device 15 with the free end being threaded through the curved groove 28 at the rear of the clamping member 21 and over the top and laid in engagement with the teeth 22 and seated within the curve 27 of said teeth, the free end then being permitted to hang downwardly as shown in Figure 1. A pull on the rope 12 when the clothes are applied to the same, thus weighting the clothes line will tend to pull the sliding clamp 21 outwardly of the housing and cause the teeth 22 to bite into the rope as the rope is being compressed between the inner face of the top 17 and the teeth 22. Due to the fact that the pull on the rope and likewise on the clamp 21 is along a line below the screws 23 and 24, the clamp will be forced outwardly and upwardly and thus prevent release of the free end of the rope while tending to prevent undue cutting or clamping of the rope by the pressure of the clamping member 21 on the end of the rope which is locked between the teeth 22 and the top 17.

I claim:

A clamp comprising a housing having a top and a side wall provided with a slot located at an angle to the horizontal, a clamping block in the housing and a plu-

rality of means secured to the block and received by the slot for guiding the clamping block towards the top of the housing, a rope adapted to have an end clamped between the 5 upper edge of the clamping block and the top of the housing, the upper gripping face of the clamping block being provided with teeth, the teeth being curved to provide a longitudinal groove to receive the rope, said 10 clamping block at the rear end thereof be-

ing provided with a groove to receive a portion of the rope which is disposed inwardly of the free end so that a pull on the rope will cause the rope to engage around the groove to exert a pressure on the block and force 15 said block towards the main body of the rope so that the teeth of the block will clamp the free end of the rope against the top of the housing.

GEORGE J. A. MOLIQUE.
